INVENTOR

M. B. Scott
BY *R. D. Smith*

his ATTORNEY

UNITED STATES PATENT OFFICE.

MERRITT BRADFORD SCOTT, OF HARTFORD, CONNECTICUT.

COLLAR-BUTTON.

SPECIFICATION forming part of Letters Patent No. 328,721, dated October 20, 1885.

Application filed July 6, 1885. Serial No. 170,729. (No model.)

To all whom it may concern:

Be it known that I, MERRITT B. SCOTT, of

Hartford, in the county of Hartford and State

of Connecticut, have invented new and useful

5 Improvements in Collar-Buttons; and I do

hereby declare that the following is a full and

accurate description of the same, reference

being had to the accompanying drawings,

wherein—

10 Figure 1 represents in perspective the sev-
eral parts of my button detached. Fig. 2 is a
transverse section of the button complete.
Fig. 3 is a longitudinal central section of the
same in use.

15 My invention consists in a collar-button pro-
vided with a post invariable in length and a
sharp-pointed stud or pin adapted to travel
therein and to be projected therefrom into the
material of the necktie to keep the same from
20 moving up or down after it has been adjusted
in place.

A and B are respectively the top and shoe
of the button. The top A is provided with a
25 tubular post, d, provided with one or more
slits, e, preferably two, on opposite sides of
said post, and a central orifice, g. The shoe
B is provided with a tubular post, h, having
a screw-thread cut in its inner surface. Said
30 shoe may have a central orifice full size of the
interior of the post h. The post h is suffi-
ciently large to pass over and inclose the
post d.

A runner, I, fitted to enter the slits e, and
35 provided on its edges with sections of screw-
thread fitted to traverse the internal threads
of the post h, is also provided, and the pointed
stud or pin k is attached to said runner.

In assembling the parts the runner may be
put in place in the slit e, and the post d then
40 soldered fast to the top A. The post h having
in like manner been soldered to the shoe B,
the post d is slipped into the post h and the
runner engaged with the screw-threads in said

post h by revolving the post d therein. When
the end of the hollow post d has been pro- 45
jected through the shoe B, the extremity of d
is milled or turned over, as shown at q, and
the parts are thereby united with freedom of
relative revolution, and when the top and shoe
are revolved relatively as to each other, the 50
runner is caused to move along the slit e, and
consequently the sharp stud or pin will be
thrust out of or withdrawn into the button, as
the case may be.

The manner of use is obvious. The button 55
is inserted in the button-hole of the shirt-band
r in front in the usual manner. The necktie
T is adjusted and then the pin is thrust out
so that its point will penetrate the material of
the tie, and thereafter prevent it from chang- 60
ing its position.

Having described my invention, I claim—

1. A collar-button having a hollow fixed
post provided with an interior screw-thread, 65
combined with a sharp-pointed stud or pin
mounted on a runner in engagement with said
screw-thread, and moved forward or back-
ward when rotated, to be concealed or thrust
out, as set forth.

2. In a collar-button, the top A, with its 70
slotted post d, fitted to enter and revolve with-
in the tubular post h, which is secured to the
shoe B, and is provided with an internal
screw-thread, combined with the runner I,
fitted to rest and move in the slotted post d, 75
and provided with a screw-thread adapted to
engage the screw-thread in the post h, and the
sharp-pointed stud or pin k, mounted on said
runner, whereby a relative revolution of said
top and shoe will cause said pin to be with- 80
drawn or thrust out, as set forth.

MERRITT BRADFORD SCOTT.
